UNITED STATES PATENT OFFICE.

EDWIN J. MURPHY AND LEONARD P. HUTT, OF SCHENECTADY, NEW YORK, ASSIGNEES
TO GENERAL ELECTRIC COMPANY, A CORPORATION OF NEW YORK.

SEARCHLIGHT.

Application filed July 9, 1920. Serial No. 394,872.

Our invention has reference to improvements in searchlights, and more specifically to a new design of arc lamp and ventilation system for use in connection therewith. The 5 arc lamp is usually housed in a barrel equipped with a suitable reflector at one end. Its opposite end may or may not have a window, our invention being adapted both to the open or closed type of searchlights.

10 One object of our invention is to provide a rugged, compact and efficient lamp unit, which may be readily placed in and removed from the searchlight barrel, and electrically connected and disconnected with 15 the operating circuit. This unit consists of a positive and a negative electrode holder or head, the positive head being arranged with the electrode in a horizontal plane, while the negative head has its electrode 20 inclined at an angle pointing upwardly toward the crater end of the positive electrode, in accordance with the usual arrangement in modern high intensity arc lamps of this general character. A mechanism is provided adjacent the positive head for rotating the anode about its axis and for feeding it forwardly to compensate for consumption. The negative head is also provided with a forward feeding mechanism. 25 The electrode heads and the feeding mechanism for the negative electrode form a compact unit, which is provided with convenient handles for placing it in position. These handles also are arranged to make the 30 electrical connections between the lamp unit and the main circuit.

35 Another object of our invention is to provide a novel system of ventilation to expel hot gases and smoke from the barrel and 40 to cool the electrode heads, the barrel and the reflector. Heretofore it has been necessary to resort to forced draft ventilation in which a motor driven fan is used, since the natural ordinary draft was insufficient, especially in high intensity searchlights. It 45 has also been found that on some occasions it is necessary to operate the searchlight at all angles of observation, for instance when exploring the sky for aircraft, which made 50 the use of the forced draft difficult. Our system depends entirely upon the natural draft or chimney effect of the heated gases. We surround the arc with a metal chamber, 55 open towards the mirror, and extending

from the bottom and top are two similar 55 draft tubes or chimneys, so arranged that either one or both of these tubes are disposed above the chamber at all angles of elevation of the searchlight. Therefore, in all positions, the gravity effect of the heated 60 gases will produce the proper chimney action to expel the hot gases and smoke.

Other objects and purposes of our invention will appear in the course of the following specification in which we have shown 65 our invention embodied in concrete form for purposes of illustration.

In the accompanying drawings, Fig. 1 is a side elevation of the lamp unit;

Fig. 2 is a side view, partly in section of 70 the negative and positive electrode heads;

Fig. 3 is a detail view of a part of Fig. 1;

Fig. 4 is a perspective view of part of the mechanism for feeding the positive electrode; 75

Fig. 5 is a section taken on the line 5—5 of Fig. 1, looking in the direction of the arrow indicated and showing the mechanism for feeding the positive electrode;

Fig. 6 is a perspective view of a searchlight embodying our invention;

Fig. 7 is a perspective view of a searchlight drum embodying our ventilation system, with our lamp unit shown in a transitory or suspended position; 85

Fig. 8 is a side view, partly in section of a closed drum type of searchlight, equipped with our ventilating system;

Fig. 9 is a front view of the closed barrel type of searchlight shown in Fig. 8, with 90 part of the ventilator omitted; and

Fig. 10 is a perspective view of part of one of the ventilating chimneys.

Referring to the drawings, there is shown in Fig. 1 a lamp unit which consists of a positive electrode head A and a negative electrode head B, which are each fully described hereinafter. These heads are secured to a common supporting plate 1, to 95 form the lamp unit shown.

A positive electrode 2, is supported in a central bore of a casting or frame 3, which frame is provided with a number of external radiating ribs 4. The plate 1 has a suitable opening through which a part of the frame 3 projects until the rib 5 nearest this end engages the plate. The frame 3 is 105 insulated from the plate 1 by a washer 6,

of mica or other suitable insulating material, and is suitably secured to said plate, as by a screw 7, which screw is surrounded by an insulating sleeve 8. The end of the frame 3 passing through the plate 1 has a wide flanged member 7' of suitable material, preferably of calorized copper set into and secured to it; the flanges of this member deflect the arc flame from the main body of the positive holder and is called an obdurator. At its opposite end, the frame 3 has a slot on its under side, extending to the central bore in the frame, into which is slidably fitted a silver faced block or contact 9, normally urged into the central bore by a spring 10. This inward movement is limited by a flange 11 on the contact 9 engaging the frame 3. When an electrode 2 is pushed into the central bore of the frame 3, the contact 9 will be urged into close engagement with the electrode, thereby making a good electrical connection.

The casting 3 is formed with an arm 12 at one end, as shown in Fig. 2, provided with a handle 13, of any suitable insulating material, such as wood or rubber.

The positive electrode 2, is arranged to move toward and away from the negative head B and to rotate about its own axis. This is accomplished by a mechanism consisting of a frame or stationary cage, indicated as a whole by the numeral 15, and a smaller cage indicated by the numeral 16, journaled within the cage 15.

The frame 15 is formed at one end by a circular member 17 having a flanged outer edge, which member is rigidly secured in any suitable manner to the base plate 1, such as by a number of legs 18, which straddle the frame 3. The other end of the frame 15 is formed by a circular member 19, somewhat similar to the member 17, and is united to said member 17 by a number of parallel rods 20, as shown in Fig. 1.

The member 17 is provided with a central opening 21, formed with a small tubular extension shown in Fig. 2, which serves as a bearing for the inner cage 16 and a passage for the positive electrode. The member 19 likewise has a central tubular extension 22, as shown in Fig. 3, which serves as a bearing for the rear end of the inner cage 16.

The inner cage 16 is formed at one end with a bevel gear 23 which has a central tubular extension 24, arranged to fit into the opening 21, as shown in Fig. 2. The rear end of the cage 16 is formed of a circular member 25, which also has a central tubular extension 26, as shown in Fig. 3. This tubular extension 26 fits over the tubular extension of the opening 22, which latter extension has been somewhat reduced in size to form a shoulder against which the member 26 abuts. The gear 23 and member 25

are connected to each other by three parallel rods 27. The cage 16 is also provided with a long screw 28, journaled at its ends eccentrically in the gear 23 and member 25, respectively. A carriage 29 is arranged to slide on the rods 27 in a suitable manner, and it has formed in it a nut which engages the screw 28. This carriage is provided with a screw clamp, indicated by the numeral 30 in Fig. 4, for clamping the rear end of the electrode 2.

From the foregoing it appears that the positive electrode 2 passes through the central bore of the frame 3, the member 24, and is at its rear end securely clamped to the inner cage by the clamp 30. This clamp is properly insulated from the carriage 29, as by mica sleeves 31. Therefore, the electrode 2 may be rotated about its own axis by rotating the cage 16, which is done by rotating a bevel pinion 32, mounted on the member 17, and which meshes with the bevel gear 23 of the cage 16.

The forward and backward movement of the electrode 2 is obtained by rotating the screw 28, which causes the carriage 29 to move. It is desirable to feed the electrode, or move it forward and rotate it simultaneously. The rotational movement is accomplished through the rotation of the bevel pinion 32. A small star wheel 33 is secured on the screw 28 near the forward end of the cage 16, and is arranged to strike a detent 34 mounted on the stationary cage 15, once during each revolution of the inner cage 16, as shown in Fig. 5. This gives a partial rotation to screw 28, and thereby a short movement to the electrode. It is obvious that the distance through which the electrode is moved by each revolution of the cage 16 is determined by the pitch of the screw 28 and by the spacing of the points of the star wheel. Sometimes it is desirable to move the electrode backward and forward rapidly without rotating it, for example, when a new electrode is placed in the lamp. For this purpose we have mounted on the screw 28 a small wheel 35, which may be readily rotated by the fingers.

The negative electrode 40 is supported in a central bore of a frame or casting 41 which is rigidly secured at one end to a supporting arm 42, and in conductive relation therewith, as shown in Fig. 2.

The supporting arm 42 is secured to the base plate 1 by screws 43, one of which is exposed in Fig. 2; the arm is suitably insulated from said plate, as by a mica washer 44. The arm 42 is so curved that the negative electrode will be held at a predetermined angle to the positive electrode 2, an angle of 14° having been found suitable. The screws 43 also secure to the base plate 1 an arm 45, which is insulated from the plate 1 by a mica washer 46. Insulating

- sleeves 46 surround the screws 43, which serve as conductors between the arm 45 and the arm 42, and insulate them from the plate 1. The arm 45 is provided with a handle 47, of insulating material, such as wood or rubber. It will also be seen that the arm 45 has a lug 10' against which the spring 10 bears, and from which it is suitably insulated such as by mica washers 11'.
 10 At its free end, the casting 41 forms a nozzle 48 which gradually tapers towards its end. Near its opposite end, the casting 41 is formed U-shaped, as indicated at 49, which serves as a housing or supporting means for the negative electrode feeding mechanism.
 15 The portion of the casting uniting the structure 49 with the nozzle 48 is of cylindrical formation and is provided with vertical openings or slots to accommodate electric contacts bearing upon the electrode. A silver contact block 50 is rigidly secured in the lower slot; it extends inwardly a slight distance beyond the wall of the central bore, so that it will hold the electrode clear of the casting. A silver brush 51 loosely fits in the upper slot so that it may engage the electrode and make a good contact with the same. The contact block 50
 20 is connected by an elastic silver band 52 with the brush 51 and is bent around the cylindrical portion of the casting 41, between the U-shaped structure 49 and the nozzle 48, which band is suitably secured to said block and brush by screws 53. The band 52, in addition to serving as a conducting bridge between the contact 50 and brush 51, also resiliently holds the brush 51 in the upper slot.
 25 The negative electrode feeding mechanism comprises a vertical support 54 suitably mounted in the U-shaped structure 49 and insulated from it. This support may be secured in position in any suitable manner, such as by providing it with a threaded end, which projects through an opening in the bottom of the U-shaped structure and securing it with a washer and nut 55. An axle 56 is journaled in a plane below the
 30 edge of the central bore in the support 54; it carries two gears 57 and 58, the former of which is somewhat smaller than the latter, and of such diameter that when an electrode rests on the contact block 50, the electrode will be in frictional engagement at its lowermost surface with said gear 57.
 35 A lever 60 is pivoted at 61 on the leg 62 of the U-shaped structure 49. A second lever 63 is pivoted to the end of lever 60 at 64, as shown in Fig. 2. At one end the lever 63, has a vertical support 65, extending downwardly in the same plane with support 54, and similar in shape with the latter. The support 65 may be secured to the
 40 lever 63 in any suitable manner by preference in the manner in which support 54 is secured to structure 49. An axle 66 is journaled in a plane above the edge of the central bore in the support 65 and carries two gears 67 and 68, preferably of the same size as gears 57 and 58 respectively.
 45 At its opposite end, the lever 63 is formed with an arm 70 which rests on the silver band 52 directly over the brush 51. An expansion spring 71 is interposed between the end 72, of the lever 60 and the end 73 of the casting 41. The lever 60 is curved to one side so that the spring 71 will not interfere with the movement of the electrode through the central bore.
 50 Obviously, the force of the expansion spring 71 will cause the lever 60 fulcrumed at 61 to press downwardly at 64. This pressure at 64 is transmitted to the lever 63, which exerts a downward pressure on the arm 70 and the axle 66. The pressure exerted upon the arm 70 is transmitted to the movable silver contact 51, so that the electrode is properly held between the contact 50 and brush 51.
 55 The force exerted upon the axle 66 causes the gear 67 to frictionally engage the electrode on its uppermost surface, and brings the gear 68 in mesh with gear 58. A suitable rotating mechanism is secured to the axle 56, such as a slidably connected rod 74 with a turn button 75, as shown in Fig. 3.
 60 The negative electrode is pushed through the central opening of the casting 41 which raises the gear 67 and releases the brush 51, thereby permitting the free passage of the electrode through the nozzle 48. The spring 71 causes the electrode to be engaged between the contact 50 and brush 51 and between the gears 57 and 67 in a manner readily understood. Obviously, by rotating the axle 56 in a clockwise direction, the gears 58 and 68 will cause the electrode to move toward and through the nose 48. It is, of course, understood that while the electrode is snugly engaged by the contacts 50 and 51, such engagement is not sufficiently rigid to prevent a sliding movement between them when the axle 56 is rotated.
 65 The electric circuit through the lamp unit thus far described is from the positive side of the source to arm 12 and the frame 3, through a braided conductor 9' to the silver contact block 9 and the electrode 2, across the arc to the negative electrode 40, contacts 50 and 51, through the frame 41, the arm 42, screws 43, and arm 45, to the negative side of the line. The connection of the line with arm 12 and arm 45 will be pointed further on.
 70 In Figs. 6 and 7 is shown an open type of searchlight of drum construction, formed of a circular frame, or ring 100, to which is secured on one side a barrel 101, forming the wall of the searchlight, and to the oppo-

site side a reflector 102, by screws 103, or in any other suitable manner, thereby closing one end of the barrel 101.

A ventilator, designated as a whole by 5 the numeral 104, is preferably formed of one casting of a length corresponding to the inside diameter of the barrel 101, and it also serves as the supporting frame for the lamp unit described, as will presently 10 appear. The ventilator casting 104 has an open central chamber 105, midway between its ends, the opening of said chamber being parallel with the axis of the barrel 101. The casting 104 is formed with two tubes 15 or chimney elements 106 and 107, leading from the chamber 105, as shown in Fig. 7, which are bent outwardly from the reflector at their ends. This casting is supported by two arms 108 and 109, which may form a 20 part of the casting and which are suitably secured to the frame ring 100. These supporting arms are of the proper length to so locate the chamber 105 that the focus of the reflector comes within the chamber. 25 The chimneys 106 and 107 are extended by similar tubular members 110 and 111, respectively, which extend nearly at right angles to chimney members 106, 107, and are rigidly secured to the casting 104 to 30 form continuous chimneys from each side of the chamber 105. The members 110 and 111 pass out of the open end of the barrel and are bent near their ends in a direction outwardly and away from the chamber 105. 35 The ends of these members are capped with cowls 112 and 113.

The barrel 101 is mounted on a yoke 114 in the usual manner to permit the movement of the searchlight through all angles 40 of elevation by the hand wheels 114'. As shown in the drawing, the casting 104 is mounted in a plane at right angles to the movement of the barrel in the yoke, so that either or both of the draft tubes 110 and 111 45 are disposed above the chamber 105 at all angles of elevation of the searchlight.

The draft tubes 110 and 111 are provided with dampers 80, one of which is indicated in Fig. 10. These dampers are pivoted at 50 116 and 117 respectively, which points it will be observed are on the inner side of the tubes, or the near side to the chamber 105, so that the damper will drop to open position in the uppermost tube and to a closed 55 position in the other, in practically all positions of the searchlight, and when not in these positions, both dampers will be open, as for instance, when the elevation of the searchlight is 90 degrees. The operation 60 of these dampers is automatic, and their movement controlled by gravity.

The conductor 118 from the positive side 65 of the line is preferably led up through the tripod 119 or other support of the searchlight, around the barrel 101. This

conductor is provided with a terminal 120, which latter is connected by means of any suitable insulated conductor with the terminal 124, mounted on the casting 104 at one side of chamber 105, and suitably insulated 70 therefrom, which terminal is provided with a screw threaded hole 125. The negative conductor 126 is connected to terminal 127, on the opposite side of the chamber 105, in a manner similar to that described with respect to the positive conductor 118. The terminal 127 is also provided with a screw threaded hole 128, similar to the hole 125. From the drawings, it will be seen that the casting 104 is provided with a pin 130 on 75 each side of the chamber 105.

The lamp unit is placed in the drum by lifting it by the handles 13 and 47, and passing the negative head B through the chamber 105, as shown in Fig. 7. The base 80 plate 1 has two openings 131 near its upper and lower ends respectively, arranged to be engaged by the pins 130 on the casting 104. The lamp unit is pushed forward in the chamber 105 until the plate 1 engages the casting 104 and the pins 130 engage the holes 131, which leaves the lamp unit supported by the casting 104 on said pins. It will also be seen that the chamber 105 is thereby closed by the plate 1, on its outer 85 end, that is, the end away from the reflector, and its inner end remains open. As stated hereinbefore, the chamber 105 occupies a position surrounding the focal point and the various parts of the lamp unit and the 90 supporting casting 104 are so coordinated that the arc may be in the focus. As described above, the electric circuit through the lamp unit is from arm 12 to the arm 45. The arm 12 is now connected to the positive 95 side of the line by means of a screw 132 of the handle 13, engaging the hole 125 of terminal 124, and the negative side is similarly connected by a screw 133 of handle 47 engaging hole 128 of terminal 127. By 100 110 this arrangement the lamp may be readily placed in or removed from the drum and the electrical connections established at the same time.

In order to be able to operate the electrode feeding and rotating mechanism from the outside of the searchlight drum, and at the same time not interfere with the easy removal or replacement of the lamp unit 115 in the drum, we have slidably connected 120 operating handles to the mechanism. In Fig. 5 is shown the operating handle 150 for the positive electrode which is fed by rotating the bevel pinion 32 as described.

This handle which is mounted on the 125 hand wheel 114' is pivotally connected to a rod 151, which passes through the member 152 on the shaft of pinion 32. A pin 153 on the shaft 151 fits into a slot in member 152, and as is readily understood, imparts the 130

motion of the shaft to the pinion. The shaft 151 passes through a cylindrical chamber 154, formed on the hand wheel 114' in which an expansion spring 155 bearing against a collar 156 on the shaft 151 normally urges the shaft inwardly towards the lamp unit. The handle 151 is formed with a convex cam surface bearing at one point against the surface of the hand wheel. Therefore, by 10 rocking the handle, the spring 155 will be compressed and the shaft 151 drawn from the slot 152, leaving the lamp unit free to be removed. With reference to the negative electrode, the shaft 56 is rotated by a handle 15, connected to a rod 74 in a manner identical with that described with respect to the handle 150 and rod 151 of the positive electrode. In Fig. 6 the handle 75 is shown in the form of a button, but otherwise the 20 mechanism is the same as described for the positive electrode. The hand wheel 114' also has the usual screen 157 for viewing the arc. A semi-circular shield 158 is mounted on or 25 forms a part of the casting 104 to permit an unobstructed view of the arc.

When our invention is used with a closed drum type of searchlight, a window 160 is fitted to the barrel 101 in any suitable manner, and is provided with two suitable openings 161 through which the chimney or draft members 110 and 111 may pass and a suitable central opening 162 for the lamp unit, as shown in Fig. 9. From Fig. 8 it will be seen that the casting 104 is positioned in the barrel slightly below the outer edge of the barrel and that the elbow ends of the chimney parts 106 and 107 thereof project slightly beyond the edge of the barrel. Therefore, when the window is in place, the ends of chimneys 106 and 107 project through the openings 161. Chimney extensions 110 and 111 are secured to parts 106 and 107 respectively; for this purpose the parts 106 and 107 are each provided 40 with a flanged edge, having inwardly directed hooks 170. These flanges are each also provided with a set of openings 171 of which one opening is shown in Fig. 8.

The parts 110 and 111 each also have a 50 flanged edge arranged to fit the flange of chimneys 106 and 107 respectively. These flanges also have a set of pins 172 arranged to fit the openings 171 and thus prevent the parts 110 and 111 from slipping out of position. The parts 110 and 111 are securely held against the chimney parts by means of a set of curved levers 173 pivoted to each of said parts and provided with rings 174 arranged to fit over the hooks 170 as shown in 55 Fig. 8, and thereby lock the parts in position in a manner readily understood. The lamp unit may be readily fitted to the casting 104 through the opening 162 in the same manner as if the glass window were not used.

60 What we claim as new and desire to se-

ure by Letters Patent of the United States, is:—

1. A searchlight comprising a source of light, a drum mounted to rotate about a horizontal axis, a reflector and a ventilating system, the latter having an open ended chamber and draft flues extending in opposite directions from the chamber substantially at right angles to the axis of the searchlight and out of the drum, the flues mounted 75 to rotate also about said axis.

2. A searchlight comprising a source of light, a drum, a reflector and a ventilating system all mounted to rotate about a horizontal axis, said system having a chamber 80 surrounding the source of light and open at its end toward the reflector, tubes extending from the chamber out of the drum in opposite directions from each other and at a substantial angle to the axis about which 85 the searchlight rotates whereby one of the tubes acts as a chimney at all angles of elevation of the searchlight.

3. A searchlight comprising an arc lamp having a light emitting element, a drum 90 mounted to rotate about a horizontal axis, a reflector and a ventilating system, the latter having an open ended chamber embracing the focal region of the reflector, means for locating the light emitting element of 95 the lamp in the focal region and draft tubes extending in opposite directions from the chamber at a substantial angle to the axis of the drum and to the said horizontal axis and out of the drum, the tubes mounted to 100 rotate also about said axis.

4. A searchlight comprising a drum and an arc lamp therein, means for mounting said drum for rotation about a horizontal axis, a ventilator for said lamp comprising 105 draft tubes mounted to rotate about said axis with the searchlight, said tubes extending in opposite directions from a point near the lamp to points outside the drum, said tubes extending substantially at right 110 angles to the axis of rotation of said drum and at a substantial angle to the longitudinal axis of the drum, a gravity damper for each tube for closing the tube when the end of the tube falls below a horizontal plane 115 through the said horizontal axis.

5. A searchlight comprising an arc-lamp, a drum, a reflector and a ventilator, the latter having an open ended chamber embracing the focal region of the reflector, means for locating the arc region of the lamp in the said focal region and for closing one end of the chamber, said ventilator having also draft tubes extending in opposite directions from the chamber substantially at right angles to the axis of the drum along a diameter of the drum and beyond the same. 120

6. A searchlight comprising an arc-lamp, a drum, a reflector whose axis coincides with that of the drum and a ventilating system, 125 130

- the latter having an open ended chamber embracing the focal region of the reflector and draft tubes extending in opposite directions from the chamber at an angle to the common axis of the reflector and drum and beyond the latter and means for turning the drum and reflector in a substantially vertical plane passing through the common axis.
10. 7. In a searchlight, a ventilator, an arc-lamp unit comprising electrode heads and a supporting plate carrying the electrode heads of the unit, said plate electrically insulated from the heads, means for securing the supporting plate with its appurtenances to and in proper relation to the ventilator, and manually actuated means for securing and releasing the supporting plate and for making and breaking the lamp circuit.
15. 8. In combination with an arc lamp having a positive electrode said lamp mounted to rotate about a horizontal axis, a double ended flue having an outlet at each end, an intake opening for said flue at a point between said ends, said arc lamp supported to register in position with said opening whereby the arc lamp may be placed with its positive electrode in any position of elevation above a horizontal position and pre-30 serve an upward draft in the flue against atmospheric pressure, said flue being located substantially at right angles to the said axis.
35. 9. In combination with an arc lamp having a positive electrode lamp mounted to rotate about a horizontal axis, a double ended flue having an outlet at each end, an intake opening for said flue at a point between said ends, said lamp supported to register in position with said opening whereby the lamp may be placed with its positive electrode in any position of elevation above a horizontal position and preserve an upward draft in the flue and a valve in40 said flue for preventing a draft flow toward the intake, said flue being located substantially at right angles to the said axis.
45. 10. In combination with an arc lamp having a positive electrode, a double ended flue having an outlet at each end, an intake opening in the flue at a point between said ends, means for rotating the lamp and flue, said lamp mounted to register in position with said opening, whereby the lamp may be placed with its positive electrode in any50 position of elevation above a horizontal po-
- sition and preserve an upward draft in the flue, and a valve mounted in said flue for preventing the reversal of the draft in the flue, said valve so mounted that when the lamp is rotated, the valve is operated.
55. 11. In combination with an arc lamp having a positive electrode, a double ended flue having an outlet at each end and an intake at a point in between, said lamp located in juxtaposition to said intake, means for rotating the lamp whereby its positive electrode may be placed in any position of elevation above a horizontal position, said flue serving to create a draft for the lamp by way of either end of the flue depending upon the position of the lamp.
60. 12. In combination with an arc lamp having a positive electrode, a double ended flue having an outlet at each end and an intake at a point in between, said lamp located in juxtaposition to said intake, means for rotating the lamp whereby its positive electrode may be placed in any position of elevation above a horizontal position, said flue serving to create a draft for the lamp by way of either end of the flue depending upon the position of the lamp, said lamp secured to said flue and electric terminals on said flue and electrical connections between said terminals and the electrodes of said lamp.
65. 13. In combination with an arc lamp having a positive electrode, a double ended flue having an outlet at each end and an intake at a point in between, said lamp located in juxtaposition to said intake, means for rotating the lamp whereby its positive electrode may be placed in any position of elevation above a horizontal position, said flue serving to create a draft for the lamp by way of either end of the flue depending upon the position of the lamp, said lamp secured to said flue and electric terminals on said flue and electrical connections between said terminals and the electrodes of said lamp, a searchlight reflector and a drum therefor, said lamp in the focal point of said reflector, said flue secured to said drum, electrical terminals on said drum and electrical connections between the terminals on the drum and the terminals on the flue.
70. 14. In witness whereof, we have hereunto set our hands this 7th day of July 1920.

EDWIN J. MURPHY.
LEONARD P. HUTT.
